(57) **CLAIM**

The ornamental design for a stand for a personal care device, as shown and described.

DESCRIPTION

FIG. 1 is a perspective view of a stand for a personal care device of the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken-line disclosure in the views is understood to form part of the article in which the claimed design is embodied, but which forms no part of the claimed design.
